SHEET PULLING DEVICE

David G. Davies, Morgantown, W. Va.

Application November 7, 1933, Serial No. 697,029

3 Claims. (Cl. 29—17)

This invention is a device for separating metal sheets as they are delivered during fabrication.

In connection with the fabrication of metal sheets there is often difficulty in separating because of their tendency to stick because of their inherent heat, and other causes, and the separation of the sheets is the cause of considerable labor and loss of time. The object of the present invention is to provide means for mechanically separating the sheets, so that they may be piled for convenient handling during further processing, and to facilitate the discovery and removal of defective sheets.

The invention will be hereinafter fully set forth and particularly pointed out in the claims.

In the accompanying drawing:—

Figure 1 is a front elevation of a sheet pulling device constructed in accordance with the invention. Figure 2 is a top plan view. Figure 3 is an end view. Figure 4 is a transverse sectional view.

Referring to the drawing, two sets of rolls A and B are provided, the sets being arranged adjacent each other, as shown in the drawing. The set A consists of a bottom roll 10 and a top roll 11, and the set B consists of a bottom roll 10a and a top roll 11a.

Each set of rolls is mounted in spaced apart vertical standards 12, secured to a base X in suitable manner, as by means of bolts 13 passed through flanges on the bottoms of the standards. Each bottom roll is provided with reduced end necks 14, which rest upon bearing blocks 15, and are retained in place by bearing blocks 16 in a manner well understood in the art of supporting rollers.

The upper rolls of each set are also provided with reduced end necks 17, said necks being rotatably mounted in blocks 18, which are vertically adjustable by any suitable means. For purposes of illustration, screw shafts 19 are shown, rotatably mounted in the upper cross bars 20 of the frame bars 12. It will be readily observed that by adjusting the screws 19, the upper roller 45 may be raised or lowered with respect to the lower roll, depending upon the direction of rotation of said screws.

The rollers 10 and 10a are provided at one end with gear wheels 21 and 21a meshing with each other, so that the said rolls will rotate in opposite directions. Rotative power is applied to either of the rolls 10 or 10a by means of any suitable prime mover, such as an electric motor 22, conventionally illustrated. Said motor may be connected with one of the lower rolls in any

suitable way, a standard type gear transmission 23, controlled by a shift lever 24, being shown for purposes of illustration, said transmission being connected with the roll 10.

It will be observed that the rolls 11 and 11a are of slightly smaller diameter than the diameter of the rolls 10 and 10a, but that the axes of the rolls of each set A and B are arranged in the same vertical plane. In this arrangement, the rolls 11 and 11a are separated laterally a greater distance than the rolls 10 and 10a. Located in the space between the rolls 11 and 11a, adjacent the tops of the rolls 10 and 10a is a guide member 30, which is of approximately triangular cross section to provide diverging guiding faces 31, 31a leading to the respective sets of rolls A and B.

In operation, the upper rolls 11 and 11a are adjusted to provide the desired clearance between them and their under rolls, and rotation is imparted to the roll 10, through the motor 22 and the transmission 23. It will be observed that the said roll 10 will rotate in one direction and that the roll 10a will rotate in the opposite direction due to the engagement of the gears 21 and 21a.

The operator first manually opens up or slightly separates the lower ends of a pair of sheets and inserts them vertically downward between the top rolls 11 and 11a, until the lower separated edges of the sheets engage with the apex of the guide member 30. As the guide member intercepts the lower edges of said sheets continued pressure upon the sheets tends to spread them in opposite directions over the surfaces 31 and 31a, bringing them into engagement with the respective sets of rolls A and B. The opposite rotation of the two sets of rolls causes the sheets to separate and move in opposite directions, the magnetism created as the result of the static electricity developed during the rotation of the rolls, serving to prevent slipping of the plates between the rolls. The result of the opposite rotation of the rolls is that the adherence between the sticking sheets is destroyed, and they are readily separated so that the operator may easily inspect them and pick out any bad sheets, without first piling them and then assorting, as is now the common practice.

The advantages of the invention will be readily understood by those skilled in the art to which it belongs. An important advantage is that the services of an operative as "a sticker puller" are dispensed with, the work is readily inspected, and time is saved in picking out the defective sheets, if any.

Having thus explained the nature of the invention,

tion and described an operative manner of constructing and using the same, although without attempting to set forth all of the forms in which it may be made, or all of the forms of its use, 5 what is claimed is:—

1. A sheet pulling device comprising two pairs of rolls, means for rotatively supporting the rolls, one roll of each pair being of smaller diameter than the other and superposed thereon in such 10 manner that their axes of rotation are in the same vertical plane, so that the larger rolls are laterally separated a smaller distance than the lateral separation of the superposed rolls, means for rotating the larger rolls in opposite directions, and 15 a guide member occupying a horizontal plane approximately corresponding to the plane of the topmost portions of the larger rolls and in line with the spaces between the larger and the smaller rolls, said guide member having diverging portions leading toward the positions between the top and bottom rolls of the respective pairs of superposed rolls whereby the sheets are delivered to 20 opposite sides of the device in general horizontal directions.
2. A sheet pulling device comprising two pairs of rotatively mounted rolls, one roll of each pair being of smaller diameter than the other and superposed thereon in such manner that their axes of rotation are in the same vertical plane, 25 so that the peripheries of the larger rolls are closer together than the peripheries of the smaller rolls, means for adjusting each smaller roll with respect to its larger lower roll in such manner as to maintain their axes in said vertical plane, 30 means for rotating the lower rolls in opposite directions, and a triangular guide member having two of its corners occupying a horizontal plane 35

approximately corresponding to the plane of the topmost portions of the larger rolls, and with its other corner located at the bottom of the spaces between the larger and the smaller rolls, the corners of said guide being connected by guide portions leading toward positions between the top and bottom rolls of the respective pairs of superposed rolls whereby the sheets are delivered to opposite sides of the device in general horizontal directions. 5

3. A sheet pulling device comprising two pairs of rolls, bearing blocks for the respective rolls of each set, said blocks being arranged in superposed pairs, the upper block of each pair being adjustable vertically, said blocks being so constructed 10 and arranged as to support the rolls of each pair, one roll of each pair of rolls being of smaller diameter than the other roll of the pair and superposed thereon in such manner that their axes of rotation are in the same vertical plane, so that 20 the larger rolls are laterally spaced a smaller distance than the lateral separation of the smaller rolls, adjusting screws for raising and lowering the upper bearing blocks, means for rotating the larger rolls in opposite directions, and a guide member occupying a horizontal plane approximately corresponding to the plane of the topmost portions of the larger rolls and in line with the spaces between the larger and the smaller rolls, 25 said guide member having diverging portions leading toward the positions between the top and bottom rolls of the respective pairs of superposed rolls, whereby the sheets are delivered to opposite sides of the device in a general horizontal direction. 30
